UNITED STATES PATENT OFFICE.

WILLIAM J. MULLALEY AND JOHN E. SCHENCK, OF CHICAGO, ILLINOIS, ASSIGNEES TO AMERICAN CAN COMPANY, OF CHICAGO, ILLINOIS, A CORPORATION OF NEW JERSEY.

RECTANGULAR CAN FOR DRIED BEEF AND OTHER ARTICLES.

No. 878,553.

Specification of Letters Patent.

Patented Feb. 11, 1908.

Application filed March 8, 1906, Serial No. 304,857.

To all whom it may concern:

Be it known that we, WILLIAM J. MULLALEY and JOHN E. SCHENCK, citizens of the United States, residing in Chicago, in the county of Cook and State of Illinois, have invented a new and useful Improvement in Rectangular Cans for Dried Beef and other Articles, of which the following is a specification.

10 Our invention relates to improvements in the construction of rectangular sheet metal cans for containing dried beef and other articles.

15 The object of our invention is to provide a rectangular sheet metal can of a simple, efficient, strong and durable construction, adapted to be hermetically sealed and conveniently opened, and having a slip cover for again closing the same after having been 20 once opened, and adapted for use for containing dried beef or other articles requiring to be hermetically sealed.

Our invention consists in the means we employ to practically accomplish this object or 25 result. That is to say, it consists in the novel construction of parts and devices and in the novel combinations of parts and devices herein shown and described and more particularly specified in the claims.

30 In the accompanying drawing forming a part of this specification, Figure 1 is a vertical, longitudinal section of a sheet metal can embodying our invention. Fig. 2 is a vertical cross section on line 2—2 of Fig. 1. 35 Fig. 3 is a horizontal section on line 3—3 of Fig. 1 and Fig. 4 is a top or plan view with the outer cover removed. Fig. 5 is a detail perspective view showing one corner of the inner cover and Fig. 6 is a similar view showing one corner of the outer or slip cover.

40 In the drawing, A represents the bottom of the can, having integral, upright sides A¹, and A² the upright ends of the can body, the same being preferably formed in separate 45 pieces from the body A and upright sides A¹. The upright sides A¹ are furnished at each end thereof with right angle flanges a, and the bottom A with similar upright flanges a¹ to receive the upright end plates A² which 50 are soldered thereto, thus forming hermetically tight joints uniting the ends A² with the bottom A and upright sides A¹. The upright sides A¹ and upright ends A² are each furnished with an inturned downwardly 55 projecting fold or flange a², which is pro-

vided with an inwardly projecting flange a³, to give the can body a smooth edge at its top and to form an inwardly projecting shoulder to receive the downturned flange of the inner thin or taggers tin hermetic cover B. The 60 thin taggers tin inner hermetic cover B is provided with integral downwardly projecting flanges b at its sides and ends adapted to fit within the mouth of the can body at the four sides thereof, and to be 65 soldered to the downwardly projecting fold or flange a² on the upright sides and ends of the can body, the horizontally or inwardly projecting flanges a³ forming a shoulder for the downturned flanges of the cover B to 70 fit against and hold the cover in place during the soldering operation, while the solder C is applied in the soldering groove or channel b¹ formed between the flange b of the cover B and the soldering flange a² on the upright 75 sides and ends of the can body.

The thin or taggers tin inside hermetic cover B is furnished with a vent b² to enable the can to be vacuumized or the air to be withdrawn therefrom after the can has been 80 filled and the cover B soldered thereon. This vent hole is soldered up in the vacuum chamber of the vacuumizing machine.

D is the outside clip cover made of ordinary or heavy tin for closing the can while its 85 contents are being used after the can has been opened by cutting out the thin or taggers tin inside hermetic cover B. The outside slip cover D has integral right angle flanges d at its sides and ends which fit over 90 and embrace the upper end of mouth of the can body.

We hereby disclaim the cans shown and described in the Mumson Patent No. 75,189, the Norton Patent No. 364,665, the Wallace 95 Patent No. 673,550 and the Ghirardelli Patent No. 746,815, our invention being the rectangular hermetic closure can hereinbefore described.

100 We claim:—

1. In a sheet metal rectangular hermetic closure can, the combination of a body A having integral upright sides A¹ and integral flanges a, said upright sides A¹ having integral right angle flanges a¹, separate piece upright ends A² soldered to said flanges on the bottom and upright side, said upright sides A¹ and ends A² having inturned downwardly projecting folds or flanges a² fitting flat thereagainst and inwardly projecting flanges a³, of 105 110

a thin or taggers tin inside hermetic covers B having downturned flanges b at its sides and ends fitting within and soldered to said downturned flanges or folds at the upper end 5 of the can body, and a slip cover D having downturned flanges fitting and embracing the upper end of the rectangular can body, substantially as specified.

2. In a sheet metal rectangular hermetic closure can, the combination of a body A having integral upright sides A^1 and integral flanges a , said upright sides A^1 having integral right angle flanges a^1 , separate piece upright ends A^2 soldered to said flanges on 10 the bottom and upright sides, said upright sides A^1 and ends A^2 having inturned downwardly projecting folds or flanges a^2 fitting flat thereagainst and inwardly projecting flanges a^3 , of a thin or taggers tin inside hermetic cover B having downturned flanges b at its sides and ends fitting within and soldered to said downturned flanges or folds at 15 the upper end of the can body, substantially as specified.

25. 3. The rectangular hermetic closure can herein shown and described and comprising a bottom with integral upright sides, separate piece ends hermetically secured at their edges to said bottom and upright sides, 30 said upright sides and ends being provided at their upper edges with inturned folds or flanges and inwardly projecting flanges fitting flat thereagainst and a hermetic closure cover having downturned flanges fitting 35 within the mouth of the can body and soldered thereto, substantially as specified.

4. The rectangular hermetic closure can herein shown and described and comprising a bottom with integral upright sides, separate piece ends hermetically secured at their edges to said bottom and upright sides, 40 said upright sides and ends being provided at their upper edges with inturned folds or flanges fitting flat thereagainst and inwardly projecting flanges and a hermetic closure 45

cover having downturned flanges fitting within the mouth of the can body and soldered thereto, said inside fitting hermetic cover having a vent to enable the can to be vacuumized after it is filled and its cover soldered in place, substantially as specified. 50

5. The rectangular hermetic closure can herein shown and described and comprising a bottom with integral upright sides, separate piece ends hermetically secured at their 55 edges to said bottom and upright sides, said upright sides and ends being provided at their upper edges with inturned folds or flanges fitting flat thereagainst and inwardly projecting flanges and a hermetic closure 60 cover having downturned flanges fitting within the mouth of the can body and soldered thereto, and an outer slip cover having integral flanges at its sides and ends and embracing the upper end of the can body, 65 substantially as specified.

6. The rectangular hermetic closure can herein shown and described and comprising a bottom with integral upright sides, separate piece ends hermetically secured at 70 their edges to said bottom and upright sides, said upright sides and ends being provided at their upper edges with inturned folds or flanges fitting flat thereagainst and inwardly projecting flanges and a hermetic closure 75 cover having downturned flanges fitting within the mouth of the can body and soldered thereto, said inside fitting hermetic cover having a vent to enable the can to be vacuumized after it is filled and its cover soldered in place, and an outer strip cover having integral flanges at its sides and ends embracing the upper end of the can body, 80 substantially as specified.

WILLIAM J. MULLALEY.
